CLAIM

We claim the ornamental design for a high voltage DC relay, as shown and described.

DESCRIPTION

FIG. 1 is a front elevational view of a high voltage DC relay according to our design;

FIG. 2 is a rear elevational view thereof;

FIG. 3 is a left-side view thereof;

FIG. 4 is a right-side view thereof;

FIG. 5 is a top view thereof;

FIG. 6 is a bottom view thereof;

FIG. 7 is a front-bottom-left isometric view thereof;

FIG. 8 is a front elevational rendering of a high voltage DC relay according to our design;

FIG. 9 is a rear elevational rendering thereof;

FIG. 10 is a left-side rendering thereof;

FIG. 11 is a right-side elevational rendering thereof;

FIG. 12 is a top elevational rendering thereof;

FIG. 13 is a bottom elevational rendering thereof; and,

FIG. 14 is a front-bottom-left isometric rendering thereof. The broken lines depict environment that forms no part of the claimed design.
